ABSTRACT

Odor formation is inhibited in paraffin hydrocarbons of boiling point range of about 100° to about 700° F by the addition of a small amount of 2,4,6-tris(dimethyl aminomethyl)phenol.

4 Claims, No Drawings

ODOR INHIBITION FOR PARAFFIN HYDROCARBONS

BACKGROUND OF THE INVENTION

This invention relates to paraffin hydrocarbons. In one of its aspects, this invention relates to odor formation in paraffin hydrocarbons. In another of its aspects this invention relates to inhibition of odor formation in paraffin hydrocarbons. In one of its concepts this invention relates to the inhibition of an odor formation in paraffin hydrocarbons by the addition of an antioxidant compound to the paraffin hydrocarbon composition.

"Odorless mineral spirits" which are generally marketed for use as paint thinner, insecticide carrier oil, charcoal lighter fluid, industrial cleaning compounds, and solvents are generally composed of a mixture of paraffin hydrocarbons having a boiling point in the range of about 100° to about 700° F. Under shelf storage conditions which include temperatures of up to 125° F or even higher, uninhibited "odorless mineral spirits" do not tend to remain odorless. It is, therefore, common practice to add an agent effective for inhibiting odor formation to commercial mixtures of these hydrocarbons. We have discovered that 2,4,6-tris-(dimethyl aminomethyl)phenol added in small amounts to paraffin hydrocarbons will inhibit oxidation and consequently the formation of odor bodies.

It is therefore an object of this invention to provide a paraffin hydrocarbon composition stabilized against oxidation that forms odor bodies. It is also an object of this invention to provide a method for stabilizing paraffin hydrocarbons against oxidation that forms odor bodies.

Other aspects, concepts and objects of this invention are apparent from the study of the disclosure and the appended claims.

SUMMARY OF THE INVENTION

According to the invention, oxidation and odor formation in paraffin hydrocarbons are inhibited by the addition of 2,4,6-tris-(dimethyl aminomethyl)phenol.

In one of the embodiments of this invention an odor inhibited composition of matter comprising at least one paraffin hydrocarbon and 2,4,6-tris-(dimethyl aminomethyl)phenol is provided.

Materials that can be inhibited against odor formation by the process of this invention are paraffin hydrocarbons, or branched aliphatic hydrocarbons, having a boiling point range of from about 100° to about 700° F. Although individual hydrocarbons boiling within this range can be inhibited by the process of this invention, the process of this invention will usually be applied to mixtures of hydrocarbons boiling within the given range. Branched aliphatic hydrocarbons having a boiling point within the range of about 240 to about 345° F such as the hydrocarbon mixtures Soltrol* 50 and Soltrol* 100, marketed by Phillips Petroleum Company have been found to be particularly well adapted to this method of odor inhibition.

The 2,4,6-tris-(dimethyl aminomethyl)phenol that has been found suitable as an odor inhibiting agent for branched aliphatic hydrocarbons is available commercially under the name DMP-30 from Rohm and Haas Chemical Co.

It has been found that even a trace of 2,4,6-tris-(dimethyl aminomethyl)phenol is sufficient to stabilize a branched aliphatic hydrocarbon composition. Usu-

ally, an amount in the range of between about 0.005 and 0.50 weight percent is used. A more preferable amount is in the range of about 0.01 to about 0.20 weight percent based on the weight of the branched aliphatic hydrocarbons being odor-stabilized. Larger amounts can be used, if desired, but we have not found the use of larger amounts necessary. In fact increased amounts could contribute to the slight "fish-like" odor present when 0.08 weight percent 2,4,6-tris-(dimethyl aminomethyl)phenol is present in Soltrol* 50.

*A registered trademark of Phillips Petroleum Company

Since the odor-stabilizing 2,4,6-tris-(dimethyl aminomethyl)phenol are soluble in branched aliphatic hydrocarbons in amounts in the range stated above, special means for introducing the 2,4,6-tris-(dimethyl aminomethyl)phenol into the hydrocarbons are unnecessary:

The cause of odor formation in branched aliphatic hydrocarbons has been determined to be the formation of oxidation products which develop upon storage of the hydrocarbons. The Example below is offered to show the effectiveness of 2,4,6-tris-(dimethyl aminomethyl)phenol in preventing oxidation and, therefore, odor formation in a mixture of branched aliphatic hydrocarbons.

EXAMPLE I

Tests were made wherein a sample (A) of Soltrol* 50 (boiling range of 240°-300° F) with 0.08 weight percent 2,4,6-tris-(dimethyl aminomethyl)phenol and a sample (B) of Soltrol* 50 alone were placed in separate bombs in an ASTM apparatus for testing oxidation stability of gasoline (ASTM Designation: D525-55). Oxygen was introduced into the bombs until a pressure of 100 psig was attained and then the bombs were placed in hot water baths at 210° F. The pressure reached 120 psig at 210° F. The percent oxygen used in the 3-day period of the tests was calculated from the pressure drop on the bomb at various time intervals.

TABLE I

No. of Days	% of Oxygen Consumed	
	A	B
0	0	0
0.5	0	3.9
1.0	0	9.8
1.5	0	22.8
2.0	0	41.3
2.5	0	70.6
3.0	0	100.0

The control (Soltrol* 50 alone)(B) had a strong oxidized hydrocarbon odor (ketone-like odor) while (A) the Soltrol* 50 with 0.08 weight percent 2,4,6-tris-(dimethyl aminomethyl)phenol was water clear, but had a slight fishlike odor.

*A registered trademark of Phillips Petroleum Company

EXAMPLE II

0.05 grams of 2,4,6-tris-(dimethyl aminomethyl)phenol was added to 100 grams of Soltrol* 50 which had been percolated over 16-30 mesh attapulgite clay (sold by the Milwhite Co., Inc., Houston, Texas) (100 ml over 105 g attapulgite clay) to remove odor from Soltrol* 50. A part of this mixture was set aside as the inhibited sample for the test report below. Similarly Soltrol* 50 which had been percolated over attapulgite clay was set aside as the control sample. Both the control and the inhibited samples were left outdoors ex-

posed to sunlight at atmospheric temperature from December 22 to June 1 in Oklahoma with the temperature varying from about 0°F. to about 100°F. The samples were stored in bottles with caps loosely attached for breathing. The samples were inspected periodically for color and odor. The results are reported in Table II below.

*A registered trademark of Phillips Petroleum Company

Table II

	No. of Days	0	8	21	83	161
Color	Control	clear	clear	clear	water clear	water clear
	Inhibited Sample	clear	sl. yellow	sl. yellow	water clear	water clear
Odor	Control	very good	very good	very good	fair	bad
	Inhibited Sample	fish-like	fish-like	fish-like	fish-like	good fair

It can be seen from the table above that the inhibited sample after developing a slight yellow color during the early part of the test period retained water clearness as did the control as test period progressed. It can also be seen from the table above that the control sample after registering a very good odor for the first 21 days of the test later deteriorated to give a bad odor after 161 days of testing. The inhibited sample while having a fishlike odor had deteriorated after 161 days only to the point of being described as having a good to fair odor.

I claim:

1. A composition of matter consisting essentially of a mixture of branched paraffin hydrocarbons having a

boiling point in the range of about 240°F to about 345°F and a stabilizing amount of 2,4,6-tris-(dimethyl aminomethyl)phenol.

2. A composition of matter of claim 1 wherein 2,4,6-tris-(dimethyl aminomethyl)phenol is present in an amount in the range of about 0.005 to about 0.50 weight percent based on the weight of the branched aliphatic hydrocarbons present.

3. A method for inhibiting odor formation in a mixture consisting essentially of branched paraffin hydrocarbons of boiling point range of about 240°F to about 345°F, said method comprising the addition of a stabilizing amount of 2,4,6-tris-(dimethyl aminomethyl)phenol.

4. A method of claim 3 wherein 2,4,6-tris-(dimethyl aminomethyl)phenol is present in an amount in the range of about 0.005 to about 0.50 weight percent based on the weight of the branched aliphatic hydrocarbons present.
